HYDRAULIC MOTOR

Theo Seifer, Berlin, Germany

Application October 19, 1937, Serial No. 169,801
In Germany October 29, 1936

8 Claims. (CL 255—4)

This invention relates to hydraulic motors operated by means of a flushing liquid in a well in which a cylinder carrying the chisel is reciprocated upwards and downwards on a piston carried by the tubing the motor being controlled by a valve influenced by control members operated by the displacement of the cylinder with regard to the stationary piston.

Motors of this kind are known by which a good impact action can be obtained. However the life of the control members is very short because they are exposed to mechanical wear, caused by the stones contained in the flushing water, and on the other hand to chemical corrosion owing to the caustic character of the flushing water in case of its penetrating caustic layers.

The object of the invention is to considerably increase the life of these control members by disposing them in a separate chamber which is tightly closed against the entrance of flushing water and may be filled with air or a liquid of any consistency. If desired, the pressure in the chamber may be lower than that of the atmospheric air. Preferably the chamber may be filled, wholly or partially with a lubricant as oil or fat.

By protecting the control members according to the invention against the influence of the flushing water I am also able to employ very sure and advantageously working control members which owing to their sensitiveness might not be used in the flushing water.

The invention is illustrated in the annexed drawings showing three modifications of especially advantageous control members.

Figs. 1 to 3^a show a modification in which the axial displacement of the valve or the valve rod is locked in the end position by resilient ring segments. Figs. 1 and 2 are vertical cross-sections of the device in different positions; Figs. 3 and 3^a show, in plan view and in vertical cross-section respectively, a detail. In the modification represented by Figs. 4, 5 and 5^a the valve rod is locked by a resilient ball-ring, Fig. 4 being a vertical cross-sectional view, and Figs. 5 and 5^a a vertical cross-section and a plan view of a detail respectively.

Figs. 6, 7 and 7^a show a modification similar to that illustrated in Figs. 1 and 2 in which the axial displacement of the valve is locked by spring rings. Fig. 6 is a vertical cross-section, Fig. 7 a detail, partly in vertical cross-section and Fig. 7^a a plan view.

Fig. 8 is an elevation, partly in vertical cross-section showing a total view of the motor and its accessories.

Referring now to Fig. 1, 1 is the tubing carrying the piston 2, on which the cylinder 3 slides upwards or downwards. The piston 2 is made hollow to form a valve chamber 4 in which the valve 5 is located. The side walls of the chamber are downwards continued to form a tube 7 of somewhat smaller diameter than the cylinder 3. The tube 7 is closed at its end by a screw plug 7a and on this is screwed a tube 7' which again is closed by a screw plug 7b. The plugs 7a and 7b have axial bores provided with stuffing boxes 6, 6 through which a rod 8 is passed which transfers the motion of the cylinder 3 to valve 5. The tube 7' encloses the control members thereby protecting them from the flushing water.

In the modification shown in Figs. 1 to 3^a the valve rod 8 is provided with a collar 10 forming at its upper and its lower side frustums of cones. These conical surfaces cooperate with ring segments 11 touching with conical outer faces the conical inner faces of the ring 12 resting on the spring 13. In the position shown in Fig. 2 the cylinder 3 occupies its lowest position and the valve is closed. The ring segments 11 lie on the upper conical surface of the collar 10 thus locking the same. When water enters the cylinder through the openings 14 in the tubing the cylinder is lifted and the spring 13 is compressed. As soon as this compression suffices to shift the ring segments 11 outwards, the control rod 8 slides upwards, whereby the valve 5 is opened.

The ring segments 11 hereby attain a position beneath the collar 10 so that the opened valve is locked. Now the water flows off, the cylinder sinks down and the spring 13 is released again.

As soon as the compression of the spring 13 is released to such an extent that the hydraulic pressure acting upon the valve 5 together with the spring 13 displaces the valve rod 8 against the resistance of the ring segments 11 downwards, the valve 5 is closed and the cylinder is again lifted.

In the modification shown in Figs. 4, 5 and 5^a the collar 10 of the valve rod 8 does not cooperate with ring segments 11, but with balls 17 held in operative position with regard to the collar by a spring ring 18. This modification further differs from that shown in Figs. 1 to 3 by the fact that here at first an auxiliary valve 19 is actuated by the valve rod 8 whereupon by the variation of the hydraulic pressure conditions the main valve 5 is opened, and a further difference consists therein that a pin or bolt 20 is inserted between the spring 9 acting to open the valve, and the cylinder 3 whereby the stroke of the valve can be

regulated and the duration of the rigid connection between the control members may be reduced to a small fraction of a second.

When in this modification the flushing water enters through the slots 14, the cylinder 3 and the rod 21 are lifted until the collar 35 fixed on the rod 21 lifts the box 22 and therewith the pin 20 until the head of the pin 20 touches the valve rod 8. On further lifting the cylinder 3, the pin 20 slides downwards through the plate 23 thereby compressing the spring 9. As soon as the head of the pin 20 strikes upon the sleeve 24 serving for regulating the stroke of the valve, a rigid connection between the control members is established, and then the cylinder 3 will displace the valve rod 8 upwards through the resilient balls 17. As soon as the utmost tension of the ring 18 has been reached and surpassed, the spring can recover its activity and now the rigid connection is released again. The balls roll along the upper cone of the collar 10 whereby the auxiliary valve 19 is opened, whereas the balls 17 under the action of the spring ring 18 are pressed beneath the collar against the valve rod and lock the latter.

When the flushing water flows off through the slots 25 after the auxiliary valve 19 is opened, the difference of pressure above and below the main valve 5 is done away with so that this valve slides downwards by its own weight and allows the water contained in the cylinder to flow off through the slots 26. Now the cylinder 3 again drops down, the valve rod 8 is taken along downwards, the plate 27 of the box 22 again striking upon the nuts 28. Now the control members are again rigidly connected with one another and the valve rod 8 is simultaneously pulled downwards overcoming the resistance of the ring 18 and again closing and locking the auxiliary valve 19. Now the water beneath the main valve 5 is arrested and as the cross-section of the valve piston is greater than that of the valve seat, the main valve is closed. The flushing water thereupon enters through the slots 14 and lifts the cylinder anew.

The modification illustrated in Figs. 6, 7 and 7a differs from that in Figs. 1 and 2 merely as regards the collar of the control rod and the locking means coacting with this collar.

The diameter of the control rod 8 is, in the casing confined by the parts 7a, 7' and 7b, increased to such an extent that a piston forms which is provided at its circumference with conical faces 29. On these faces slide spring rings 30 having interior conical faces and being inserted between rings 31, 31. The rings 31 are secured to the parts 7a or 7b respectively. The head 32 of the valve rod is connected with the lower end of the valve 5 in such a manner that a small play is provided between the ends facing each other. In the upper and in the lower ring 31 holes 33 are bored through which oil is circulated. When the piston of the rod 8 reaches its end positions, the holes are closed and an impact of metal against metal is prevented.

When the cylinder 3 slides upwards, also the box 34 is lifted and the spring 9 is compressed, until the valve rod 8 is pressed upwards and the slanting surfaces 28 are shifted through the rings 30, whereby the valve 5 is opened. When the conical surfaces 29 and 30 have been displaced with respect to each other to such an extent that both slanting surfaces of a single inner ring touch one slanting surface of each of the adjacent outer rings, the compression of the spring 9 is con-

sumed to such an extent that the rings can no longer be displaced and the valve 5 is locked in open position. While the water flows off through the opened valve the cylinder 3 sinks down and therewith the box 34, so that the valve rod 8 is drawn downwards by the box 34 with the nut 28 and the conical surfaces 29 are again shifted downwards through the resilient outer rings 30, whereby the valve is closed.

I claim:—

1. In a hydraulic motor operated by means of a flushing liquid in a well, the combination of a hollow shaft, a piston connected with said shaft, a cylinder slidably enclosing the piston, a chisel carried by said cylinder, the piston being provided with an opening, a valve adapted to close said opening and to reverse the movement of the cylinder, members arranged between the cylinder and the piston controlling the valve, a casing secured to the piston enclosing the said members, and means within the said casing for locking the said members in their end positions.

2. In a hydraulic motor operated by means of a flushing liquid in a well, the combination of a hollow shaft, a piston connected with said shaft, a cylinder slidably enclosing the piston, a chisel carried by said cylinder, the piston being provided with an opening, a valve adapted to close said opening and to reverse the movement of the cylinder, members arranged between the cylinder and the piston controlling the valve, a spring adapted to open the valve, a casing secured to the piston enclosing the said members and the said spring, and means within the said casing for locking the said members in their end positions.

3. In a hydraulic motor operated by means of a flushing liquid in a well, the combination of a hollow shaft, a piston connected with said shaft, a cylinder slidably enclosing the piston, a chisel carried by said cylinder, the piston being provided with an opening, a valve adapted to close said opening and to reverse the movement of the cylinder, members arranged between the cylinder and the piston controlling the valve, a casing secured to the piston enclosing the said members and containing a lubricant, and means within the said casing for locking the said members in their end positions.

4. In a hydraulic motor operated by means of a flushing liquid in a well, the combination of a hollow shaft, a piston connected with said shaft, a cylinder slidably enclosing the piston, a chisel carried by said cylinder, the piston being provided with an opening, a valve adapted to close said opening and to reverse the movement of the cylinder, members arranged between the cylinder and the piston controlling the valve, a spring adapted to open the valve, a casing secured to the piston enclosing the said members and the said spring, a lubricant in the said casing, and means within the said casing for locking the said members in their end positions.

5. In a hydraulic motor operated by means of a flushing liquid in a well, the combination of a hollow shaft, a piston connected with said shaft, a cylinder slidably enclosing the piston, a chisel carried by said cylinder, the piston being provided with an opening, a valve adapted to close said opening and to reverse the movement of the cylinder, a casing secured to the piston, a valve rod sliding in the said casing and provided at its portion in the casing with a collar tapered at its upper and its lower end, ring segments arranged surrounding the said collar tapered at their inner and outer surface, a conical ring carrying the

- said segments, a spring carrying the said conical ring, and a spring tending to open the valve inserted between the said valve rod and the cylinder.
- 5 6. In a hydraulic motor operated by means of a flushing liquid in a well, the combination of a hollow shaft, a piston connected with said shaft, a cylinder slidably enclosing the piston, a chisel carried by said cylinder, the piston being provided with an opening, a valve adapted to close 10 said opening and to reverse the movement of the cylinder, a casing secured to the piston, a valve rod sliding in the said casing and provided at its portion in the casing with a collar tapered 15 at its upper and its lower end, a row of balls arranged to surround the said collar, a spring ring pressing the said balls in a certain position against the valve rod and in another position against the said collar, a spring inserted between the valve and the cylinder tending to open the valve, 20 a bolt slidably arranged with regard to the cylinder and acted upon by the last-named spring, and an exchangeable sleeve determining the stroke of the valve in which sleeve the said bolt slides.
7. In a hydraulic motor operated by means of a flushing liquid in a well, the combination of a hollow shaft, a piston connected with said shaft, a cylinder slidably enclosing the piston, a chisel carried by said cylinder, the piston being provided with an opening, a valve adapted to close 25 said opening and to reverse the movement of the cylinder, a casing secured to the piston, a valve rod sliding in the said casing and provided, at its portion sliding inside the casing, with a piston the surface of which forms a number 25 of cones, a number of spring rings having conical inner surfaces coacting with the said cones, and a spring inserted between the said valve rod and the cylinder tending to open the valve.

THEO SEIFER. 30
